UNITED STATES PATENT OFFICE.

CLARENCE L. WHEELER, OF MARION, INDIANA, ASSIGNOR OF ONE-HALF TO
JAY WILLARD CLARK, OF SAME PLACE.

CAR-SEAL.

SPECIFICATION forming part of Letters Patent No. 446,107, dated February 10, 1891.

Application filed June 2, 1890. Serial No. 353,975. (No model.)

To all whom it may concern:

Be it known that I, CLARENCE L. WHEELER, of Marion, in the county of Grant and State of Indiana, have invented a new Improvement 5 in Car-Seals; and I do hereby declare the following, when taken in connection with accompanying drawings and the letters of reference maked thereon, to be a full, clear, and exact description of the same, and which said drawings constitute part of this specification, and represent, in—

Figure 1, a view in perspective of my improved car-seal; Fig. 2, a view thereof in section, showing the hooked ends of the strap 15 just after their introduction into the disk or button and before they are caught together to form the seal; Fig. 3, a similar view showing the same parts after the seal or lock has been formed; Fig. 4, a detached broken view 20 looking upon the rear of the disk or button; Fig. 5, a view in transverse section of said disk or button and the inner ends of the strap on line *a b* of Fig. 4; Fig. 6, a detached view, in inside elevation, of the filling for the said 25 disk or button; Fig. 7, a modification.

My invention relates to an improvement in seals designed particularly for freight-cars, the object being to produce a simple and inexpensive seal adapted to be operated solely 30 by hand and sealed without the use of any tools or stamps and constructed so that it cannot be picked or opened without breaking it or without showing plainly that it has been tampered with.

With these ends in view my invention consists in a strap provided at both ends with a hook and a disk or button composed of two cups and a filler, one of the said cups having two slots in its bottom to receive the respective 35 ends of the strap and the filler having a recess to form a clearance-space for the same.

My invention further consists in certain details of construction and combination of parts, as will be hereinafter described, and pointed 40 out in the claims.

My improved seal comprises a narrow flexible sheet-metal strap *A*, having its ends bent upon themselves to form oppositely-turned hooks *B B*, which practically correspond to 45 each other in length.

My seal also comprises a disk or button composed of the outer cup *C* and the inner cup *C'*, which are secured firmly together by drawing the flanged edge of the outer cup over the inner cup. The bottom of said inner cup *C'* of the said disk or button is provided with two parallel slots *D D*, through which the hooks at the ends of the strap are respectively inserted into the disk or button and slid beyond each other until one 55 escapes the other, after which they are pulled together to complete the lock, as shown by Fig. 3 of the drawings. These hooks are elastic, so that although they readily contract to pass through the slots before mentioned, 60 and to slide by one another when introduced into the disk and until they escape each other in the disk, they then spring open again in such a manner that their ends cannot be cleared of each other by any direct or end 65 thrusts of the hooks, and the hooks drawn together, as seen in Fig. 3, interlock with each other. The width of the opening of the hook is greater than the distance between the face side of the space in the disk and the open end 70 of the other hook. Consequently one cannot pass the other so as to separate the hooks to permit the withdrawal of either one or the other. The side or lateral manipulation of the hooks is prevented by the filling-wad *E*, 75 located within the disk or button, composed of paper, wood, or other suitable material and provided with a recess *F*, formed in one of its sides and arranged in alignment with the two openings *D D*, which open into its opposite 80 ends. The side walls of this recess or space prevent the hooks from being moved laterally or sidewise and disengaged by side or lateral thrusts, as before referred to. It will thus be seen that as soon as the hooked ends of the 85 strap have been introduced into the button or disk and pushed beyond each other, their ends cannot after that be cleared from each other, so as to permit them to be pulled out of the button or disk. It is also apparent that 90 no instrument can be introduced into the button or disk in such a way as to disengage the hooks without defacing the seal so far as to clearly show that it has been tampered with. 95 Instead of preventing the lateral movement 100

of the hooks, whereby disengagement might be produced by the introduction of a filling, the inner cup may be shaped, as seen in Fig. 7, so that a diametrical recess corresponding to the recess described, as in the filling, may be made as an integral part of the cup.

The disks are made complete as an article of manufacture and furnished to the consumers, and may be stamped or embossed with any desirable device to indicate particular cars, location applied, or whatever indicating mark it is desirable to apply thereto.

I claim—

1. In a car-seal, the combination, with a strap provided at each end with an elastic metallic hook, of a disk or button composed of two cups secured together so as to leave a space between them, one of said cups constructed with two slots through which the respective hooks of the strap may be introduced, and

with a recess between the cups in line with said slots and in width corresponding substantially to the width of said slots, the said hooks being adapted to pass each other within the said recess and engaged by their elasticity, substantially as described. 25

2. In a car-seal, the combination, with a strap provided at each end with an elastic metallic hook, of a disk or button composed of two cups secured together, and a recessed filling located within the said button or disk, one cup of which is provided with two slots in line with said recess and through which the respective hooks of the strap may be introduced and slid past each other, after which they expand and lock, substantially as described. 30 35

CLARENCE L. WHEELER.
